US0D1109014S

(12) **United States Design Patent** (10) **Patent No.:** **US D1,109,014 S**
(45) **Date of Patent:** **** Jan. 13, 2026**

(54) **STRAP DOUBLE PIN BUCKLE**

(71) **Applicant:** **Shenzhen Zhixing Sichuang Technology Co., Ltd.**, Guangdong (CN)

(72) **Inventor:** **Hai Jun Feng**, Guangdong (CN)

(***) **Term:** **15 Years**

(21) **Appl. No.:** **29/905,201**

(22) **Filed:** **Oct. 17, 2023**

(30) **Foreign Application Priority Data**

Jun. 5, 2023 (CN) 202330339529.6

(51) **LOC (15) Cl.** **02-07**

(52) **U.S. Cl.**

USPC **D11/234**

(57) **CLAIM**

The ornamental design for a strap double pin buckle, as shown and described.

DESCRIPTION

FIG. 1 is a perspective view of the strap double pin buckle showing my new design;

FIG. 2 is a perspective view thereof from another angle;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view of thereof; and,

FIG. 8 is a bottom plan view of thereof.

The broken line portions are shown for illustration purposes and form no part of the claimed design.

1 Claim, 8 Drawing Sheets
